RICHARD WITTY, OF CHICAGO, ILLINOIS.

Letters Patent No. 94,371, dated August 31, 1869.

IMPROVEMENT IN STEAM-ENGINE PISTONS.

The Schedule referred to in these Letters Patent and making part of the same.

To all whom it may concern:

Be it known that I, RICHARD WITTY, of Chicago, in the county of Cook, and in the State of Illinois, have invented certain new and useful Improvements in Pistons for Steam-Engines; and do hereby declare that the following is a full, clear, and exact description thereof, reference being had to the accompanying drawings, and to the letters of reference marked thereon, making a part of this specification.

The nature of my invention consists in the construction and arrangement of a piston-head, with valves so that a portion of the steam may be re-worked.

In order to enable others skilled in the art to which my invention appertains, to make and use the same, I will now proceed to describe its construction and operation, referring to the annexed drawings, which represent a vertical section of a piston-head, with valves attached.

A represents the piston and B the follower, placed a suitable distance apart, and through the centre of which the piston-rod passes, the space between the piston and follower to be closed at the outer circumference by a metal ring.

In the piston A are placed valve-seats *a a*, and in the follower B are a corresponding number of valve-seats *a' a'*.

Spindles *b b* are then passed through the same, which are at each end provided with a valve, *d*, said valves being held on the spindle by jam nuts *e e*, and on each end of the spindle is placed a spiral spring, *i*, which extends beyond the spindle, as seen in the drawings.

The valve-seats *a* and *a'*, which may be of any number desired, are so placed in the piston and follower

that when the valves on either side are closed, said valves shall be flush, or even with the surface of the piston, or follower, and the spindles *b b* are of such length, that at the proper time both valves on each spindle will be open, allowing free passage of the steam through the piston.

The valves will be closed at the commencement of the stroke by the pressure of steam from the boiler, and are opened by coming against the cylinder-head a little before the stroke is completed, and then both valves will be open, allowing a steam-passage through the piston.

The springs *i i*, on the ends of the spindles, of course relieve the concussion or shock against the cylinder-head.

The steam that is to be reworked will, when both valves are opened, as above mentioned, then pass through the piston, and as soon as the piston commences to return, the valves on the other side are closed in like manner, the exhaustible steam in the position expanding the ring or rings that surround the piston.

Having thus fully described my invention, What I claim as new, and desire to secure by Letters Patent, is—

The construction and arrangement of the valve-seats *a a'*, spindles *b b*, valves *d d*, nuts *e e*, and springs *i i*, with reference to the piston A and follower B, all substantially as shown and described.

In testimony that I claim the foregoing, I have hereunto set my hand and seal, this 29th day of May, 1869.

RICHARD WITTY. [L. S.]
